UNITED STATES PATENT OFFICE.

JOHN SABATINO, OF NEW YORK, N. Y.

MASSAGE APPARATUS.

1,173,039.

Specification of Letters Patent.

Patented Feb. 22, 1916.

Application filed December 31, 1913. Serial No. 809,669.

To all whom it may concern:

Be it known that I, JOHN SABATINO, a subject of the King of Italy, and a resident of the city of New York, Richmond Hill, 5 borough of Queens, county of Queens, and State of New York, have invented a new and Improved Massage Apparatus, of which the following is a full, clear, and exact description.

10 This invention relates to improvements in massage apparatus, and particularly to a holding device for the vibrator, and has for an object to provide an improved structure whereby the hand of an operator may be 15 properly connected with the vibrator so as to give an even firm vibration.

Another object of the invention is to provide a holding device arranged with suitable straps for connecting the hand of the operator, which straps are renewable, and are 20 adapted to be brought under tension so as to clamp the hand more or less firmly to the holding device.

25 A further object of the invention is to provide a holding device which will fit the hand correctly, and allow all of the hand to be used, if desired.

30 A still further object of the invention is to provide tension means for operating the clamping straps, whereby the clamping straps may be quickly and easily adjusted to any size hand.

In carrying out the object of the invention the holding device is associated with a vibrator of any desired kind, as for instance of the same variety as disclosed in my Patent 1,069,814, issued August 12, 1913. The particular form of the vibrator forms no part of the present invention, but in order to be 35 associated with the present invention it must be provided with a handle or projection over which the supporting member of the holding device embodying the invention is fitted. This projection or member is preferably 40 formed integral with the body of the holding device so that the vibrations from the vibrator may be directly communicated to the holding device and from thence to the hand clamped by the holding device. The clamping means is preferably a pair of straps which are adjustably connected on one side of the device, and are wound upon a rotatable shaft on the opposite side, whereby the 45 straps may be adjusted simultaneously or independently for fitting the hand of an operator. Locking means are associated with

the shaft for locking the same at any point of its rotation.

In the accompanying drawings—Figure 1 is a side view of an embodiment of the invention, a hand being shown clamped thereto and a vibrator being shown associated therewith; Fig. 2 is a top plan view of the holding device; Fig. 3 is an end view of the holding device; Fig. 4 is a detailed fragmentary sectional view through a slightly modified form of locking means for the tape roller.

Referring to the accompanying drawings by numeral 1 indicates a vibrator of any desired kind provided with a shaft 2 which is designed to be rotated by any suitable means, whereby vibrator 1 will be properly actuated. Associated with the vibrator 1 is a holding device 4 adapted to be vibrated, whereby the hand 5 of the operator which is clamped to the holding device will be properly vibrated and thus allow the fingers to act as massage members. The holding device 4 is provided with a body or base 6 which has preferably formed integral therewith an upstanding bracket 7 formed with an aperture 8 for accommodating the shaft 2. A set screw 9 is provided in bracket 7 for clamping the same 70 rigidly to shaft 2 so that the vibrations will be directly communicated to base 6. The bracket 7 may be arranged at any desired angle in respect to the sides of base 6, but preferably at a considerable angle, as shown 75 in Fig. 2, so that the power shaft 3 will be cut out of the way of the operator. The base 6 may be of any desired size, preferably comparatively small, and preferably of substantially the width of the ordinary hand so 80 that the clamping straps or tapes 10 and 11 may be connected to opposite sides of the base and be caused to properly clamp the hand. On one edge of the base 6 are arranged extensions 12 and 13 provided with 85 slots 14 and 15 through which the ends of straps 10 and 11 project. Suitable spurs 16 and 17 are provided which are pivotally mounted. These spurs are arranged to engage the straps or tapes 10 and 11 and hold 90 the same against movement, whereby each strap may be independently adjusted. The opposite side of base 6 carries a rotating shaft 18 to which the straps 10 and 11 are buttoned, whereby both straps are adjusted 95 simultaneously. This is very desirable as 100 after the straps have been properly adjusted 105

so that strap 11 will clamp properly a hand across the palm and strap 10 will properly clamp the two central fingers, the shaft 18 is utilized for loosening and again tightening the straps as the device is applied and then removed. However, if a different hand is used, the ends of the respective straps may be adjusted by causing the spurs 16 and 17 to engage different points on the straps. Shaft 18 is rotatably mounted in upstanding brackets 19 and 20 and carries a ratchet wheel 21 which is rigidly connected thereto by any desired means, as for instance set screw 22. Ratchet wheel 21 is adapted to engage a pawl 23 which is pivotally mounted at 24 to bracket 7. The lower part of pawl 23 is provided with an extension 25 which if desired may be forced against the ratchet wheel 21 and act as a brake. A suitable spring 26 is provided for normally forcing pawl 23 into continuous engagement with ratchet wheel 21. As the thumb member 27 on shaft 18 is rotated the tapes 10 and 11 will be wound on shaft 18, and said shaft will be prevented from reverse rotation by the action of pawl 23. Of course, whenever desired, pawl 23 could be moved out of engagement with ratchet wheel 21 so that the shaft 18 will be free to rotate in either direction, and the tapes may be properly loosened for removing the hand.

In Fig. 4 will be seen a slightly modified form of locking means for shaft 18, whereby the same is locked substantially in any of its adjusted positions. Apertures or depressions 28 are provided in the end of the shaft which is mounted on bracket 20', whereby the end of set screw 29 arranged in bracket 20' may engage the shaft 18 so as to lock the same against rotation. It will also be evident that numerous other locking means may be provided for preventing a reverse rotation of the shaft 18 after the tapes have been properly tightened.

As shown in Fig. 2, the base 6 is formed with openings 30 through which stitching or securing means 31 are passed for connecting pads 32 and 33 to base 6. It is of course evident that other securing means may be provided for securing these pads in place, though the means described is simple and effective, and is therefore preferably used. In order to cause the tapes 10 and 11 to properly clamp the hand and fingers against the pads, slots 34 and 35 are provided in base 6 opposite slots 14 and 15, as shown in Fig. 2.

In operation, the pawl 23 is actuated so as to release ratchet wheel 21 and tapes 10 and 11 are consequently loosened. The hand is then thrust through tape 11 until the same strikes against the thumb, as shown in Fig. 1, and the second and third fingers are thrust through tape 10. Shaft 18 is then rotated until one or both of the tapes have

been tightened to the desired extent for clamping hand 5 against pads 32 and 33. If one of the tapes should not properly clamp the hand the end of the said tape adjacent the respective resilient spurs 16 and 17 will be pulled until the tape is acting properly. The power is then turned on and as the vibrator 1 operates the holding device 4 will vibrate, and consequently hand 5 will vibrate. The fingers are then pressed against the person being operated upon and a proper massage effect will be produced. To remove the device the power is turned off the vibrator and then pawl 23 is operated for releasing ratchet wheel 21, whereupon the tapes will become loosened and the hand may be easily withdrawn therefrom.

It is evident that any form of tape or strap may be used, but preferably a more or less resilient tape is used so that there will be a resilient gripping effect of the tape against the hand. It is evident that the brackets supporting the shaft 18 could be of any desired size so that the tape wound on the shaft 18 may be of an appreciable length. This is desirable where different persons are to be massaged with the same device. In a case of this kind, the tape is unrolled from shaft 18 and drawn past the retaining spurs on the opposite side of base 6 and cut off so that the used tape is removed, and new tape is provided. This prevents any of the used or old tape coming in contact with the new patron. In arranging the tapes 10 and 11 on shaft 18 the same may be secured thereto in any desired manner, a desirable way being the use of a button 36 for each of the tapes. In arranging any particular kind of tape in position the same may be slotted and then placed over the respective buttons 36 and wound properly on shaft 18. In unwinding the tape and pulling out the soiled sections the finger or hand uses extensions 12 and 13 as a fulcrum when pulling the tapes. This is especially desirable after the shaft 18 has been locked and the tapes are being pulled to individually fit the respective parts of the hand. It will also be observed in Fig. 2 that strap 10 is provided with a cross bar 37 pressed by a spring extension 38 of the clamping member 39.

What I claim is—

1. In an apparatus of the character described, a base, a bracket projecting from said base for connecting the base with a vibrator, said base being formed with pairs of spaced apertures, each pair of said apertures being on opposite sides thereof, and directly opposite each other, said base being also provided with ears adjacent certain of said apertures for acting as fulcrums, a tape extending through each pair of apertures for clamping a hand to said base, means for connecting one end of each of said tapes to said base, said means overlapping said ful-

crumpled extensions, whereby the tapes may be properly pulled for fitting the hand, and adjustable means for adjustably connecting the ends of said tapes to said base.

5 2. In an apparatus of the character described, a holding device for a vibrator comprising a base, means for connecting said base with the vibrator, a pair of straps or tapes independently and adjustably connected with said base from one side, a rotatable shaft connecting said straps on the opposite side of said base, a ratchet wheel connected with said shaft, a spring pressed pawl acting on said ratchet wheel for preventing a reverse rotation thereof, whereby said straps may be independently adjusted on one side of said base, and simultaneously adjusted on the opposite side of said base, and a brake associated with said pawl adapted to engage 15 said ratchet wheel for breaking the motion thereof when the pawl releases said ratchet wheel.

3. In an apparatus of the character described, a base, a bracket projecting from said base for connecting said base with a vibrator, said base being formed with a pair of apertures on opposite sides thereof, said apertures being in alignment, a tape extending through each pair of apertures for clamping a hand to said base, means for connecting one end of each of said tapes to said base, and adjustable means for adjustably connecting the opposite ends of said tapes to said base.

35 4. In an apparatus of the character described, a holding device for a vibrator comprising a base, means for connecting said base with a vibrator, cushioning means arranged on one side of said base, a pair of straps for clamping a hand against said cushioning means, means arranged on one side of said base engaging said straps for connecting the straps to said base, and a rotatable shaft connected with said straps 40 at the opposite side of said base for simultaneously moving said straps so as to clamp said hand to said base.

5. In an apparatus of the character described, a holding device for a vibrator comprising a base, means for connecting said base with a vibrator, a pair of straps independently connected with said base on one side, a rotating shaft connecting said straps on the opposite side of said base, a ratchet wheel connected with said shaft, and a pawl for normally preventing a reverse 55 rotation of said ratchet wheel, whereby said straps may be independently connected to said base and simultaneously adjusted on the opposite side of said base.

6. In an apparatus of the character described, a base, a bracket projecting from said base for connecting the base with a

vibrator, said base being formed with pairs of apertures, each pair of said apertures being on opposite sides of the base and directly opposite each other, a tape extending through each pair of apertures for clamping a hand to said base, means for connecting one end of each of the tapes to said base 65 adjacent one side of the base and adjustable means adjacent the opposite side of the base for adjustably connecting the opposite ends of said tapes to said base.

7. In a massage apparatus of the character described, a holding device for a vibrator comprising a base, means for connecting said base with a vibrator, a pair of straps or tapes independently and adjustably connected with said base on one side 70 thereof, a rotatable shaft connected with said straps on the opposite side of said base, and means associated with said shaft for locking the same against rotation.

8. In an apparatus of the character described, a holding device for a vibrator comprising a base, means for connecting said base with said vibrator, a pair of straps or tapes independently connected with said base on one side thereof, a rotatable member connected with said straps on the opposite side of said base for adjustably connecting said straps to that side of said base, means acting on said rotatable member for preventing the rotation thereof, and a brake 85 for breaking the action of said rotatable member when said means releases the rotatable member.

9. In a massage apparatus of the character described, a holding device for a vibrator, comprising a base, means for connecting said base with a vibrator, a pair of straps independently connected with said base on one side, a rotatable member connected with said straps on the opposite side of said base, said 100 straps being adapted to be wound on said rotatable member, and means for locking said rotatable member against accidental operation.

10. In a massage apparatus of the character described, a base, a bracket projecting from said base for connecting the base with a vibrator, a tape for clamping a hand to said base, means for connecting one end of said tape to said base adjacent one side of 110 the base, and an adjustable means adjacent the opposite side of the base for adjustably connecting the opposite end of said tape to said base.

In testimony whereof I have signed my 120 name to this specification in the presence of two subscribing witnesses.

JOHN SABATINO.
